WINDOW CONSTRUCTION

Glenn F. Seliger, Marathon, Wis., assignor to Marmet Corporation, Wausau, Wis., a corporation of Wisconsin
Filed Nov. 13, 1961, Ser. No. 151,923
10 Claims. (Cl. 20—53)

This invention relates to a casement window unit and more particularly to an improved sash locking mechanism for a casement window.

In an outward swinging casement window unit, one side edge of the sash is hinged to the frame of the window and the window is generally opened and closed by a crank mechanism. In addition to the crank mechanism, a locking device is employed to draw the sash in tightly against the frame and lock the sash.

In recent years the trend has been toward higher or taller windows having a height of three to four feet. Because of the flexibility of the materials, two locking devices are generally needed to draw the sash into the frame and lock the same. One locking unit is located at the bottom portion of the sash and the second locking unit is located at the upper portion of the sash so that the entire height of the sash will be drawn firmly in toward the frame. In some cases separate locks are employed at both the upper and lower portions of the sash, but separate locks are not too practical for frequently the upper lock is so far above the floor level that it is difficult to reach and operate. Therefore, multiple point locking mechanisms are generally employed in which a single operating member or handle is mechanically connected to two or more locking members so that by operating the handle, the locking members will engage and draw the sash in at various locations along its height and lock the same to the frame.

The present invention is directed to an improved locking mechanism for a casement sash and particularly to a multiple point locking mechanism. The locking mechanism of the invention includes a vertical rod which is journaled within a series of bearing blocks on the frame. Both the upper and the lower ends of the rod are bent at about a 90° angle to the body of the rod.

The lower bent end of the rod is located between a pair of fingers connected to an operating handle pivotally mounted on the frame. As the handle is depressed, the fingers move up and by a cam action, the lower bent end of the rod is rotated and pivoted into engagement with a flange on the sash to draw the sash toward the frame. Simultaneously, the upper bent end of the rod is also pivoted and brought into contact with the flange at the upper portion of the sash to draw the upper portion of the sash tightly against the frame.

The bent ends of the rod are not located in a common plane but instead, the upper bent end is advanced or displaced at a small angle from the plane of the lower bent end and this enables the upper bent end to engage the sash before the lower bent end engages the sash, resulting in a torque being set up in the operating rod which causes the top end to hold the sash more securely.

The locking mechanism of the invention is of simple construction and is less costly, particularly less costly to mount due to a minimum of milling operations, than the conventional type of locking mechanism. Furthermore, all of the operating mechanism is located on the frame and this avoids the necessity of mounting some of the parts on the sash.

The locking mechanism exerts a force at spaced locations along the height of the sash which draws the sash against the frame and locks the sash to the frame. No mechanical linkage is required and this greatly simplifies the construction and reduces the cost. Furthermore, the

2

mechanism of the invention is capable of engaging and drawing in a sash which is located up to $\frac{5}{8}$ inch from the frame. This is a considerably greater "draw-in" than can be accomplished with the conventional locking mechanism which normally will draw in a sash only up to $\frac{3}{16}$ inch.

Other objects and advantages will appear in the course of the following description.

The drawings furnished herewith illustrate the best mode presently contemplated of carrying out the invention.

In the drawings:

FIG. 1 is a front elevation of the casement window unit employing the locking mechanism of the invention;

FIG. 2 is a cross sectional view taken along line 2—2 of FIG. 1 and showing the sash in the locked positions;

FIG. 3 is a perspective view showing the locking mechanism in the closed position;

FIG. 4 is a view similar to FIG. 3 and showing the locking mechanism in the open position;

FIG. 5 is an enlarged elevational view of the operating handle; and

FIG. 6 is an enlarged elevational view of the operating rod.

The drawings illustrate a casement window unit which includes a generally rectangular frame 1 and a sash 2 which is hinged along its side edge to the frame 1. The sash is adapted to be opened or closed with respect to the frame by either a mechanical crank, not shown, or manually by a handle which is attached to the sash.

The frame 1 includes a jamb 3 and an inner flange 4 extends outwardly from the inner edge of the jamb while an outer flange 5 extends in the opposite direction from the outer edge of the jamb. In addition, a small central flange 6 extends laterally from the jamb adjacent the inner edge and in the same direction as the flange 4.

The sash 2 includes a jamb 7 and an outer flange 8 extends laterally from the jamb and is adapted to overlap the flange 6 of the frame when the sash is in the closed position. To seal the joint between the flange 8 and the flange 6, a weather stripping bead 9 of rubber, plastic or the like, is secured within a groove or recess 10 which extends throughout the length of the flange 8.

In addition to flange 8, sash 2 also includes a small central flange 11 which is adapted to overlap the outer portion of the inner flange 4 of the frame when the sash is in the closed position, and an inner flange 12 which is disposed along the inner edge of the jamb 7 and extends in the opposite direction from the flanges 8 and 11. As in the case of flange 8, the flange 11 is provided with a groove or recess 13 and a suitable weather stripping material 14 is disposed within the recess and is adapted to seal the joint between the flange 11 and the flange 4.

A pane of glass 15 is secured to the sash 2 and the peripheral edge of the glass is embedded within a glazing compound 16 which is retained in place by a glazing bead 17. The bead 17 is locked to the sash by means of a pair of deformable lips 18 which are engaged beneath shoulders 19 formed in the recess 20 in the jamb 7 of the sash.

According to the invention the sash 2 is drawn against and locked to the frame 1 by means of a rod 21 which is journaled within a pair of bearing blocks 22 and 23 secured to the jamb 3 of the frame. The upper end 24 of the rod 21 is bent at an angle of about 90° to the body of the rod and similarly, the lower end 25 of the rod 21 is also bent at an angle of about 90° to the body of the rod.

Each of the bearing blocks 22 and 23 is composed of a pair of half sections 26 and 27 having complementary grooves 28 and 29 which receive and journal the rod 21. The half sections 26 and 27 are secured to the jamb 3 by means of screws 30. As best shown in FIG.

6, the pair of washers 31 are located on the rod and are maintained against the upper surface of the lower bearing block 23 and against the lower surface of the upper bearing block 22 by upset nipples 32. The washers maintain the proper positioning of the rod within the bearing blocks and prevent the rod from moving up during rotation.

The rod 21 is rotated to move the ends 24 and 25 of the rod into engagement with the flange 11 on the sash by an operating member 33 which includes a pair of fingers 34 and 35. The finger 34 is disposed in a plane generally parallel to the plane of the jamb 3, while the finger 35 extends outwardly at an angle to this plane and functions as a cam to pivot the lower end 25 of the rod when the operating member is moved within the plane parallel to jamb 3. The outer end of the finger 34 is provided with a tapered end portion 37 to prevent accidental displacement of the bent end 25 of the rod from the recess 36.

The operating member 33 is disposed within an opening in the jamb 3 and is pivotally connected to a bifurcated housing 38 by a rivet 39. An operating handle 40 is connected to the outer portion of the operating member 33 and by raising or lowering the handle, the operating member will be pivoted around the rivet 39 to thereby rotate the rod 21.

To limit the downward movement of the handle a stop 41 is connected to the operating member and is adapted to engage the outer surface of the flange 4 to limit the downward movement of the handle.

The housing 38 includes a generally flat upper portion 42 which is secured to the flange 4 by means of a screw 43. The lower portion 44 of the housing is bifurcated and the operating member 33 is pivotally connected in the bifurcated section 44 by rivet 39, as previously described.

The lower portion of the housing 38 terminates in a pair of notched feet 45, having notches 46 which are adapted to engage the edge of the opening in the flange 4 and thereby maintain alignment of the housing within the opening.

In assembling the locking mechanism, the operating member 33 and housing 38 are initially connected together as an integral unit by means of the rivet 39. The housing 38 is then positioned within the opening in the flange 4 with the notches 46 engaging the edge of the opening. The upper end portion 42 of the housing is then secured to the flange 5 by the screw 43.

After the housing has been attached to the frame, the rod 21 is positioned within bearing blocks 22 and 23 and the lower end 25 of the rod is disposed within the recess 36. The bearing blocks 22 and 23 are then secured to the jamb 3 by means of the screws 30.

In the unlocked position the bent ends 24 and 25 of the rod are normally disposed against the jamb 3 of the frame or in a plane generally parallel to the jamb. When the sash is closed by the operating crank, not shown, the flanges 8 and 11 of the sash will not be tightly held against the corresponding flanges 6 and 4 of the frame. To draw the sash tightly against the frame, the handle 40 is depressed, causing the fingers 34 and 35 to move upwardly. Upward movement of the cam finger 35 serves to rotate or pivot the lower end 25 of the rod, thereby causing a corresponding pivoting of the upper end of the rod to bring the bent ends 24 and 25 of the rod into contact with the flange 11 to move the flange into tight contact with the flange 4 of the frame and seal the joint therebetween.

To unlock the sash, the handle is raised and the fingers 34 and 35 will move downwardly thereby rotating the lower end 25 and upper end 24 to a position generally parallel to the jamb 3. With the ends 24 and 25 in this position, the sash can then be opened without interference with the bent ends of the rod.

In order to provide a positive holding action for the upper end of the window, the upper end of the rod 21 is not disposed in a common plane with the lower end

5 of the rod, but instead is located in a plane at an angle of 5° to 10° with respect to the lower end. It has been found that if the upper end of the rod is advanced about 7° toward the sash with respect to the lower end of the rod, the upper end of the rod will thereby engage the flange 11 before the lower end of the rod engages the flange, with the result that a torque is set up in the rod 21 causing the upper bent end 24 to hold the sash more securely.

10 The locking mechanism of the invention is of simple construction and requires less milling operations to install than the conventional type of locking device. Furthermore, the entire locking mechanism is located on the frame and this avoids having to mount operating parts on both the frame and the sash.

15 The bent ends of the rod are able to engage and draw in a sash which is up to $\frac{1}{8}$ inch out of closing with respect to the frame. This is a substantially greater "draw-in" power than that of conventional units, most of which will have a "draw-in" power of only $\frac{3}{16}$ inch.

20 The locking mechanism is particularly adaptable to a multiple point window in which the operating mechanism operates to draw the sash in along a plurality of points along the height of the sash. However, it is contemplated that the operating mechanism can be used with a single point locking mechanism for a shorter casement window. In this case, the rod 21 would be cut off above the lower bearing block 23 and the bent lower end 25 of the rod would be the only member serving to engage 25 and draw the sash to the frame.

20 Various modes of carrying out the invention are contemplated as being within the scope of the following claims particularly pointing out and distinctly claiming the subject matter which is regarded as the invention.

35 I claim:

1. A casement window unit, comprising a frame section having an opening and having a pair of opposed jambs bordering the opening, a sash section disposed within the opening and hingedly connected to a first of the jambs of the frame section, said frame section having an abutment extending laterally from the second of said jambs toward the sash section and said sash section having a complementary abutment extending laterally toward the second jamb and adapted to bear against said abutment when the sash section is in the closed position, a rod rotatably secured to one of said sections and disposed generally parallel to said jambs, a pair of locking members connected at spaced locations to the rod with each locking member disposed at an angle with respect to the axis of the rod, an actuating member disposed in direct engagement with one of said locking members and movable in a plane substantially parallel to the plane of the jamb, said actuating member disposed to pivot said locking member about the axis of the rod when said actuating member is moved in a plane substantially parallel to said jambs, and an operating member operably connected to the actuating member for moving said actuating member within the plane to thereby pivot each locking member into engagement with the abutment on the other of said sections to draw the abutments together and lock the sash section to the frame section.

50 2. The structure of claim 1 in which one of said locking members is disposed in a plane at an angle to the plane extending through the other locking member so that the first-named locking member will engage said projection before said second locking member when the rod is rotated.

55 3. A casement window unit, comprising a frame having an opening and having a pair of vertical opposed jambs bordering the opening, a sash disposed within the opening and hingedly connected to a first of the jambs and adapted to be opened and closed with respect to the frame, said frame having an abutment extending inwardly from the second of the jambs toward the sash and said sash having a complementary projection extending outwardly toward

said second jamb and adapted to engage said abutment when the sash is in the closed position, a vertical elongated member rotatably secured to said second jamb, a first locking member connected to the elongated member and disposed at the lower portion of the sash, a second locking member connected to the elongated member and disposed at the upper portion of the sash, each of said locking members being disposed in a substantially horizontal plane, an actuating member disposed in direct engagement with said first locking member and disposed to pivot said first locking member about the axis of the elongated member, and an operating member located on the inside of the window unit and operably connected to the actuating member for actuating the same and pivoting said first locking member about the axis of said elongated member and simultaneously pivoting said second locking member about said axis, each locking member being engageable with the projection on the sash to draw the projection against the abutment on the frame to thereby lock the sash to the frame at a plurality of positions along the height of the sash.

4. A casement window unit, comprising a frame having an opening and having a pair of vertical opposed jambs bordering the opening, a sash disposed within the opening and hingedly connected to a first of the jambs and adapted to be opened and closed with respect to the frame, said frame having an abutment extending inwardly from the second of the jambs toward the sash and said sash having a complementary projection extending outwardly toward said second jamb and adapted to engage said abutment when the sash is in the closed position, a vertical elongated member rotatably secured to said second jamb, a first locking member connected to the elongated member and disposed at the lower portion of the sash, a second locking member connected to the elongated member and disposed at the upper portion of the sash, each of said locking members being disposed in a substantially horizontal plane, said second locking member being disposed in a vertical plane displaced angularly from a vertical plane through said first locking member and in a direction toward said sash whereby said second locking member engages the projection on the sash before said first locking member engages said projection to thereby create a torque in the rod to provide an increased sealing effect, an actuating member disposed in direct engagement with said first locking member and disposed to pivot said first locking member about the axis of the elongated member, and an operating member located on the inside of the window unit and operably connected to the actuating member for actuating the same and pivoting said first locking member about the axis of said elongated member and simultaneously pivoting said second locking member about said axis, each locking member being engageable with the projection on the sash to draw the projection against the abutment on the frame to thereby lock the sash to the frame at a plurality of positions along the height of the sash.

5. A casement window unit, comprising a frame having an opening and having a pair of vertical opposed jambs bordering the opening, a sash disposed within the opening and hingedly connected to a first of the jambs and adapted to be opened and closed with respect to the frame, said frame having an abutment extending inwardly from the second of the jambs toward the sash and said sash having a complementary projection extending outwardly toward said second jamb and adapted to engage said abutment when the sash is in the closed position, a vertical elongated member rotatably secured to said second jamb, a first locking member connected to the elongated member and disposed at the lower portion of the sash, a second locking member connected to the elongated member and disposed at the upper portion of the sash, each of said locking members being disposed in a substantially horizontal plane, said second locking member being disposed in a vertical plane displaced angularly from a vertical plane

through said first locking member and in a direction toward said sash whereby said second locking member engages the projection on the sash before said first locking member engages said projection to thereby create a torque in the rod to provide an increased sealing effect, an actuating member including a pair of fingers and having a recess between said fingers to receive said first locking member, one of said fingers being disposed in a plane substantially parallel to said jamb and the other of said fingers being disposed in a plane at an angle to said first named plane whereby said second finger operates as a cam to rotate said first locking member about the axis of the elongated member when the actuating member is moved in said first named plane, and a handle connected to the frame and located on the inside of the window unit, said handle being connected to the actuating member and serving to move said actuating member in said first named plane to thereby rotate said locking members into engagement with the projection on the sash to draw the projection against the corresponding abutment on the frame and lock the sash to the frame.

6. A locking mechanism for a casement window having a frame section and a sash section hinged to the frame section and adapted to be opened and closed with respect to the frame section, comprising a rod rotatably mounted on a jamb portion of one of said sections, a pair of locking members connected to the rod with each locking member disposed at an angle with respect to the axis of the rod, an actuating member mounted for movement in a plane parallel to said jamb portion and including a pair of fingers and a recess located between said fingers, one of said locking members being disposed within said recess, and cam means associated with one of said fingers for rotating the locking member about the axis of the rod as the actuating member is moved parallel to said jamb portion to thereby bring said locking members into engagement with the other of said sections to draw the sash section against the frame section.

7. A casement window unit, comprising a frame having an opening and having a pair of vertical opposed jambs bordering the opening, a sash disposed within the opening and hingedly connected to a first of the jambs and adapted to be opened and closed with respect to the frame, said frame having an abutment extending inwardly from the second of the jambs toward the sash and said sash having a complementary projection extending outwardly toward said second jamb and adapted to engage said abutment when the sash is in the closed position, a vertical elongated member rotatably secured to said second jamb, a first locking member connected to the elongated member and disposed at the lower portion of the sash, a second locking member connected to the elongated member and disposed at the upper portion of the sash, each of said locking members being disposed in a substantially horizontal plane, an actuating member having a pair of fingers and having a recess between the fingers to receive said first locking member, one of said fingers having a cam surface extending at an angle with respect to the jamb, means for pivotally connecting the actuating member to the frame for movement in a plane parallel to the jamb, and a handle connected to the actuating member and serving to pivot the actuating member in said plane to thereby rotate the locking members into engagement with the projection on the sash to draw the projection against the corresponding abutment on the frame and lock the sash to the frame.

8. A casement window unit, comprising a frame having an opening and having a pair of vertically opposed jambs bordering the opening, said frame also including a pair of spaced abutments extending laterally outward from one of the jambs toward the other jamb, a sash disposed within the opening and hingedly connected to said other jamb and adapted to be opened and closed with respect to the frame, said sash having a pair of abutments extending laterally outwardly from the sash in spaced relation and engageable with the respective abutments of the

frame when the sash is in the closed position, a rod located in the space between the abutments on the frame and rotatably secured to said frame, a first locking member connected to the lower portion of said rod, a second locking member connected to the upper portion of said rod, and an actuating member located in the space between the abutments on said frame and disposed in direct engagement with one of said locking members, and an operating handle connected to the actuating member for moving said actuating member and thereby pivot said locking members into engagement with one of the abutments on said sash to draw said abutment against the corresponding abutment on the frame.

9. The structure of claim 8 in which the actuating member is pivotally connected to the frame about a horizontal axis for movement in a vertical plane and the outer portion of the actuating member extends through a vertically extending slot in the frame.

10. A locking mechanism for a casement window having a frame section and a sash section hinged to the frame section and adapted to be opened and closed with respect to the frame section, comprising a rod rotatably mounted on one of said sections, a plurality of locking members connected to the rod and disposed at an angle with respect to the axis of the rod and adapted to be

5 moved into engagement with the other of said sections to lock the sections together, one of said locking members being located adjacent the upper portion of the sash section and a second of said locking members being located adjacent the lower portion of said sash section, said first 10 locking member being disposed in a plane at an angle to the plane extending through the other locking member and advanced in a direction toward said other section so that said first locking member will engage said other section before said second locking member when the rod is rotated, and means disposed in direct engagement with the second locking member for rotating the rod about the axis thereof to pivot said locking members into engagement with said other section to thereby lock the sections together.
